UNITED STATES PATENT OFFICE.

BENJAMIN N. BRODIO, OF NEW YORK, N. Y., ASSIGNOR TO THE SUPERHEATER COMPANY, OF NEW YORK, N. Y., A CORPORATION OF DELAWARE.

SEPARATELY-FIRED SUPERHEATER.

Application filed June 9, 1924. Serial No. 718,695.

This invention relates to superheaters and particularly to separately fired superheaters as distinguished from that type of superheaters constructed as a part of, or installed 5 in, an ordinary steam boiler.

It is the principal object of this invention to provide a new and improved construction of a separately fired superheater which will be of such high thermal efficiency as to make 10 the use thereof practical from an economical standpoint. Another object is to combine with such a superheater, means for heating the feed water supplied to the boiler; a part of such means being constructed and 15 arranged to act as a protective screen for those portions of the superheater which are subjected to the greatest heat.

These and other more specific objects will 20 appear from the following description and by reference to the accompanying drawings, which illustrate an example of my invention without defining its limits, and wherein, Fig. 1 is a longitudinal vertical section taken substantially on the line 1—1 of Fig. 2; Fig. 25 2 is a plan view and Figs. 3 and 4 are sections on the lines 3—3 and 4—4 respectively of Fig. 1.

As the specific details of the furnace or 30 fire box portion of the apparatus form no part of the present invention, only a small portion thereof has been shown in the drawings in order to permit the construction and mounting of the superheater units to be shown on a larger scale. A fire wall 11 35 which extends across between the side walls 12 and 13 serves to divide the furnace or fire box chamber 10 from the superheater chamber 14 and terminates at a point approximately half way between the top and bottom of the structure to provide an inlet 40 for the furnace gases to the chamber 14. A wall 15 extends longitudinally along the central part of the chamber 14 and a plurality of transversely extending baffle walls 45 16, 17 and 18 are provided within said chamber to define a tortuous passage for the products of combustion from the furnace through the superheater chamber. The walls 16 and 18 terminate short of the floor 50 of the chamber to provide the passages 19 and 20 and the wall 17 terminates short of the top wall thereof to provide a passage 21. It will be noted that the passages defined by the baffle walls decrease in horizon-

tal cross-sectional area from the front to 55 towards the rear of the apparatus to offset the shrinkage due to the cooling of the gases.

An inlet manifold 22, which extends parallel to and above the side wall 12, is provided with the lateral branches 23, 24 and 60 25, to which the inlet headers 26, 27 and 28 are connected. The header 26 extends transversely across the top of the structure at the front end thereof and in alignment with the front wall 11; and the headers 27 and 28 extend across in alignment with the walls 65 16, and 18. An outlet manifold 30, located adjacent to the side wall 13, is provided with the lateral branches 31 and 32 to which the outlet headers 33 and 34 are connected. 70

A plurality of rows of superheater tubes or units are mounted within the superheater chamber and are suitably connected to the inlet and outlet headers. Each superheater unit consists of a plurality of lengths of 75 tubing, connected at their adjacent top and bottom ends by a return bend 40 preferably united to the tubing by a special forging operation which forms each unit into an integral structure of great strength and durability. As the first loops 35^a of the units 35 of the first row are exposed to the hottest gases, the units 35 are made into two separable sections 35^a and 35^b, connected by a double ball coupling joint 35^c so as to permit 85 the replacement of the first loop without necessitating the replacement of the second loop. The loops 35^a of the first units are 90 preferably arranged in staggered relation as shown in Fig. 1, while the loops of the remaining rows are arranged in alignment transversely of the apparatus. The units 35 are connected at their front and rear ends respectively to the inlet header 26 and outlet header 33; the units 36 of the second row 95 to the inlet header 27 and outlet header 33; the units 37 of the third row to the inlet header 27 and the outlet header 34; and the units 38 of the last row to the inlet header 28 and the outlet header 34. Spacing plates 100 42, and 43 are provided at suitable points to hold the units in proper position.

The units 35 which form the first steam pass are preferably of heavier tubing than the other units to withstand the higher temperatures to which they are subjected, and said units 35 are also of shorter overall length than the other units to decrease the 105

resistance to the steam flow and thereby increase the velocity of the steam in this pass; thus increasing the protection against burning out of these units.

- 5 A plurality of horizontally extending baffles 45 are placed in the last gas passage between the baffle walls 17 and 18 to cause the gases to flow across the tubes, and thereby obtain a greater heat exchange between 10 the gases and tubes. The provision of these baffles also helps to decrease the effective area of the gas passage and thereby assists in increasing the velocity of the gases in this passage.

- 15 A water screen, which consists of a plurality of pipes 46, 46^a preferably arranged in two closely spaced vertical rows with the pipes of each row staggered relatively to those of the adjacent row, extends across the 20 space above the fire wall 11; one end of said pipes being connected to the vertically extending inlet header 47 and the other end of said pipes being connected to the outlet header 48. It will be noted by referring to 25 Fig. 3 that the pipes 46, 46^a are inclined upwardly from the inlet header 47 towards the outlet header 48 to permit the escape of any bubbles which might be formed within said pipes. It will also be noted that the 30 spaces between adjacent pipes 46, 46^a, increase gradually from the bottom towards the top of the water screen, thereby providing a freer passage for the gases towards the top and a relatively restricted passage 35 towards the bottom. This arrangement insures a better distribution of the gases over the entire water screen and over the first row of superheater units, and also serves to afford better protection of those parts of 40 the units located nearest to the fire bed.

- An economizer 49 of any suitable construction, placed within the last or outlet pass 50 of the superheating chamber, serves to give a preliminary heating to the feed water 45 for the boiler. The water enters the economizer at the top thereof, through the supply header 51, and flows through the economizer in counter-flow with respect to the gases, that is to say from the top to the bottom 55 thereof. The feed water then passes from the economizer through the outlet header 52 which is connected by the pipe 53 with the vertical inlet header 47 of the water screen. While the arrangement described by connecting the water screen and the economizer 60 may be resorted to in many installations, it will be obvious that it is within the spirit of my invention, in cases where it may be found desirable to supply water for two different purposes, as for example, feed water, and water for process or other uses, the water screen and economizer will not be connected. In such cases, therefore, separate 65 supply and outlet pipes for the water heating members will be employed.

It will be noted that saturated steam is introduced into both the first and last passes of the superheater, the steam flowing counter to the gases in the last units 38 so that the last heat is taken from the gases by the 70 coolest steam and to secure the most efficient heat exchange by counter flow in accordance with the well known laws of thermo-dynamics.

In the first units 35 the steam flow is parallel to the gas flow so as to furnish better protection to the loops 35^a nearest the fire, the coolest steam passing through these loops first.

The provision of the water screen ahead 80 of the superheater units serves to protect the superheater units as it acts as a heat absorbing surface to cool the gases before they contact with the superheater units and also performs the function of a checkered 85 wall, breaking up the flame and preventing it from impinging directly on the superheater units 35. As the water screen contains water while the superheater units contain steam, the temperature of the pipes 46 90 will be less than the loops 35^a, therefore there will be a heat exchange between the loops 35^a and the pipes 46 of the water screen, which will also tend to prevent burning out 95 of these loops.

The construction of the inlet and outlet manifolds, the headers connected thereto and the manner in which the superheater units are connected to the headers provide an assembly which is very elastic, that is to 100 say, one in which the capacity of the apparatus may not only be readily increased or decreased as desired, but which also permits the replacement of any units, to be easily and quickly accomplished.

105 While I have shown the water screen as constructed of two rows of pipes 46, both rows being connected to a common header on each side of the apparatus, it will be obvious that two or more headers may be supplied 110 on each side, and also that in addition to using the water or other fluid from the water screen and economizer for two different purposes, the fluid heated in the water screen may also be employed for different purposes 115 by resorting to the expedient of using separate, unconnected headers for any number of the pipes 46. Instead of using two rows of pipes 46 it will also be obvious that only one row or that 120 any number of rows of pipes may be substituted. Again while I have described the pipes 46 as forming a water screen, it is apparent that the principles of construction are not limited to the use of water in such 125 pipes, but that any heat absorbing fluid may be circulated either through such pipes or through the economizer.

130 It will be understood that the number of rows of units employed, the number of units

in each row, the location of the headers and the use of manifolds will be varied according to the requirements of the plant, and that other changes, variations and modifications of the constructional details may be adopted without departing from the spirit of my invention.

I claim:

1. In a separately fired superheater, a furnace, a superheating chamber having an inlet communicating with said furnace and an outlet, said chamber being provided with a plurality of baffle walls arranged to provide for the furnace gases a tortuous passage consisting of separate gas passes connected in series, said passage decreasing progressively in cross sectional area from said inlet towards said outlet, a plurality of groups of superheater units mounted within said superheating chamber and forming a plurality of separate steam passes arranged in parallel, each of said separate steam passes being contained entirely within a separate gas pass, and means to supply the steam to be superheated to said plurality of separate passes.

2. In a separately fired superheater, a furnace, a superheating chamber having an inlet communicating with said furnace and an outlet, said chamber being provided with a plurality of baffle walls arranged to provide a tortuous passage for the furnace gases, said passage decreasing in cross sectional area from said inlet towards said outlet, a plurality of groups of superheater units mounted within said tortuous passage at different distances from said furnace and arranged to provide a plurality of separate steam passes connected in parallel and means to supply the steam to be superheated to said plurality of separate passes.

3. In a superheater, a furnace, a plurality of groups of superheater units arranged to form a first pass located closest to the furnace, a last pass located farthest from the furnace and a plurality of intermediate passes, and means to cause the steam to flow in parallel through said passes, in uniflow and counterflow with the furnace gases through said first and last passes respectively.

4. In a separately fired superheater, a furnace, a superheating chamber having an inlet communicating with said furnace and an outlet, a plurality of separate groups of superheater units mounted within said chamber through which the steam to be superheated is conducted in separate passes, one of said groups of superheater units being located adjacent to said inlet and another of said groups being located adjacent to said outlet, and means to supply saturated steam to each of said last named groups of units in separate passes in parallel relationship, in uniflow with the furnace gases in the first

named group and in counterflow with the furnace gases in the last named group of superheater units.

5. In a superheater, a furnace, a plurality of groups of superheater units arranged to form a plurality of separate parallel steam passes located at different distances from said furnace, and means to cause the steam to flow through the first of said steam passes nearest to the furnace in uniflow with the furnace gases and in the pass farthest from said furnace in counterflow to the furnace gases, said first pass being of such shorter length than the last pass that substantially the same degree of superheat is imparted to the steam in each of said passes.

6. In a separately fired superheater, a furnace, a superheating chamber having an inlet communicating with said furnace through which the furnace gases flow, a plurality of superheater units mounted within said chamber and arranged in spaced rows at different distances from said furnace, an inlet manifold and an outlet manifold, and connections therefrom to said superheater units to cause the steam to pass in separate parallel steam passes through said rows, the first row of units immediately adjacent to said furnace being of shorter overall length than the units of the remaining rows whereby the steam flow through said first row of units will be at a greater velocity than the flow through said remaining rows.

7. In a separately fired superheater, a furnace, a superheating chamber having an inlet communicating with said furnace, said chamber being provided with a plurality of baffle walls to provide a tortuous passage of decreasing cross sectional area for the furnace gases through said chamber, a plurality of superheater units arranged in spaced parallel rows at different distances from said furnace and projecting into said chamber between said walls, an inlet manifold, an outlet manifold and connections from said manifolds to said units to cause the steam to be passed in parallel through said units in a plurality of separate steam passes.

8. In a separately fired superheater, a furnace, a superheating chamber having an inlet communicating with said furnace, said chamber being provided with a plurality of baffle walls to provide a tortuous passage of decreasing cross sectional area for the furnace gases through said chamber, a plurality of superheater units arranged in spaced rows at different distances from said furnace, and projecting into said chamber between said walls, an inlet manifold, an outlet manifold and connections from said manifolds to said units to cause the steam to be passed through said units in a plurality of separate parallel steam passes, and a plurality of baffles arranged in said chamber and extending across the last rows of superheater units to reduce

the effective cross sectional area of, and thereby increase the velocity of the gases in, that part of the gas passage in which said last rows are located.

- 5   9. In a separately fired superheater, a furnace, a superheating chamber having an inlet communicating with said furnace, said chamber being provided with a plurality of baffle walls to provide a tortuous passage of
10   decreasing cross sectional area for the furnace gases through said chamber, a plurality of superheater units arranged in spaced rows at different distances from said furnace and projecting into said chamber between said walls, an inlet manifold, an outlet manifold and connections from said manifolds to said units to cause the steam to be passed in parallel through said units in a plurality of separate steam passes, and a plurality of baffles arranged in said chamber and extending across the last rows of superheater units to reduce the effective area of, and increase the velocity of the gases in, that part of the gas passage adjacent to said last rows, the rows of units adjacent to said furnace being of shorter overall length than the remaining rows to cause the steam to flow therethrough at a greater velocity than through the remaining passes. 35
15
20
25   10. In a separately fired superheater, a furnace, a superheating chamber having an inlet communicating with said furnace, said chamber being provided with a plurality of baffle walls to provide a tortuous passage of
30   decreasing cross sectional area for the furnace gases through said chamber, a plurality of superheater units arranged in spaced rows at different distances from said furnace and projecting into said chamber between said walls, an inlet manifold, an outlet manifold and connections from said manifolds to said units to cause the steam to be passed in parallel through said units in a plurality of separate steam passes, and a plurality of baffles arranged in said chamber and extending across the last rows of superheater units to reduce the effective area of, and increase the velocity of the gases in, that part of the gas passage adjacent to said last rows, the rows of units adjacent to said furnace being of shorter overall length than the remaining rows to cause the steam to flow therethrough at a greater velocity than through the remaining passes. 40
35
40
45

inlet communicating with said furnace, said chamber being provided with a plurality of baffle walls to provide a tortuous passage of decreasing cross sectional area for the furnace gases through said chamber, a plurality of superheater units arranged in spaced rows at different distances from said furnace and projecting into said chamber between said walls, an inlet manifold, an outlet manifold and connections from said manifolds to said units to cause the steam to be passed in parallel through said units in a plurality of separate steam passes, and a plurality of baffles arranged in said chamber and extending across the last rows of superheater units to reduce the effective area of, and increase the velocity of the gases in, that part of the gas passage adjacent to said last rows, the rows of units adjacent to said furnace being of shorter overall length than the remaining rows to cause the steam to flow therethrough at a greater velocity than through the remaining rows.

In testimony whereof I have hereunto set my hand.

BENJAMIN N. BROIDO.
